UNITED STATES PATENT OFFICE

2,193,599

FASTENER-APPLYING DEVICE

Arthur H. Maynard, Warwick, and Joseph M. Gamba, East Greenwich, R. I., assignors to Boston Wire Stitcher Company, Warwick, R. I., a corporation of Maine

Application December 12, 1938, Serial No. 245,106

6 Claims.

(Cl. 1—3)

This invention is a continuation in part of our prior United States Letters Patent, No. 2,181,904, granted Dec. 5, 1939, and relates to improvements in fastener-applying devices for attaching papers and other sheets, securing tags and labels to articles of commerce and for use generally in fastening or stitching together various objects and articles.

One object of the invention is to provide an implement of the type indicated adapted for applying the fasteners to the work to form either a permanent flat stitch or a temporary pin-stitch.

Another object of the invention is to provide an implement of the type indicated having a sliding anvil with selective means for effecting either a flat permanent stitch or a temporary pin-stitch.

Another object of the invention is to provide an implement of the type indicated wherein the fastener-applying means is held in raised position with respect to the work supported directly on the base of the implement until a fastener has been driven through the work and thereafter moved toward the work to engage the ends of the projecting legs of the fastener with clinching means on the base.

Another object of the invention is to provide an implement of the type indicated wherein the yielding means for holding the fastener-applying means raised with respect to the work on the base is carried by an arm on which the stapling means is mounted, either forwardly or rearwardly of the fastener-driving means.

Another object of the invention is to provide means for retaining the work in fixed position on the base of the implement throughout the fastener-applying operation.

Still another object of the invention is to provide an implement of the type indicated which is of simple and compact construction and proof against derangement or getting out of order.

Further objects of the invention are set forth in the following specification which describes several forms of construction of the implement, by way of example, as illustrated by the accompanying drawings. In the drawings:

Fig. 1 is a perspective view of one type of implement incorporating the novel features of the present invention;

Fig. 2 is a part-sectional view of the implement showing the anvil adjusted in position to form a pin-stitch and the hand-lever depressed to drive a staple while the stapling arm is held in raised position with respect to the work;

Fig. 3 is a part-sectional view similar to Fig. 2

showing the stapling arm depressed into engagement with the work to cause the legs of the driven staple to be bent or clinched:

Fig. 4 is a transverse sectional view of a portion of the stapling arm showing the means for attaching the elevating spring to the arm;

Fig. 5 is a transverse sectional view on line 5—5 of Fig. 2 showing the legs of the driven staple projecting from the stapling arm while the latter is held in raised position with respect to the work;

Fig. 6 is a view similar to Fig. 5 showing the legs of the staple as having been bent outwardly by the camming grooves in the anvil as the stapling arm is moved toward the base to form a pin-stitch;

Fig. 7 is a view similar to Fig. 5 showing the ends of the legs of the staple projecting from the stapling arm and engaging a different set of camming grooves in the anvil;

Fig. 8 is a view similar to Fig. 7 showing the legs of the staple as having been bent inwardly by the camming grooves as the stapling arm is moved toward the base to form a permanent stitch;

Fig. 9 is a part sectional view of an implement of modified form of construction having a bowed spring mounted on the arm forwardly of the driver and engageable with the work to maintain the arm raised with respect to the base and to hold the work in place thereon:

Fig. 10 is a side elevational view of the forward portion of the implement illustrated in Fig. 9 showing the stapling arm moved toward the base against the action of the bowed spring; and

Fig. 11 is a side elevational view of an implement of another modified form of construction having a spring-pressed plunger carried by the arm forwardly of the driver and engageable with the work to maintain the arm raised with respect to the base and to hold the work in place thereon.

Although the invention is herein shown and described as embodied in an implement for applying U-shaped wire staples it may be applied to devices for applying other types of fasteners. A standard type of desk stapler has a stapling arm embodying a magazine for the staples pivotally mounted on a base and staple-applying mechanism at the end of the arm adapted to cooperate with an anvil on the base. With this type of implement a spring is provided for holding the stapling arm raised with respect to the base to permit the work to be inserted therebe-

tween. When the implement is operated the spring yields to permit the arm to first move toward the base to grip the work thereagainst and the driver is thereafter operated to drive 5 a staple. As the staple is driven the ends of the legs are engaged by clincher-grooves in an anvil on the base and the clincher-grooves act to continuously bend and clinch the legs as they are driven.

10 It has heretofore been proposed to provide a device for first driving a staple through the work and thereafter forcing its straight, projecting legs outwardly to form a flat stitch, but such previously used implements require special clinching 15 means or other elements to cause the legs to be bent at their points of joinder with the crown without deformation. In the Maynard United States Patent No. 1,506,073, issued August 26, 1924, an arched spring-plate is mounted on the 20 base overlying the clinching anvil to act to hold the work suspended above the anvil until the legs of the staple are driven therethrough. After the legs of the staple have been driven through the work the force applied causes the spring- 25 plate to yield to effect engagement of the ends of the legs with camming grooves in the clincher-anvil. In the Cavanagh United States Patent No. 2,149,839, issued March 7, 1939, a work-supporter is pivotally mounted on the frame of the 30 implement and is first operated to hold the work suspended above the anvil while a staple is driven therethrough. The work-supporter then yields to cause the ends of the staple-legs to be engaged with camming grooves in the anvil whereby to 35 bend the legs into parallel relation to the crossbar to form a flat stitch.

In accordance with the present invention the spring for holding the stapling arm in raised position with respect to the base is made sufficiently stiff to resist movement of the arm toward the 40 work directly supported on the base until after the staple-driver has been actuated to penetrate the legs of the staple through the work. In other words, the spring for holding the stapling arm raised is more resistant than the spring for holding the staple-driver in raised position on the arm. After the legs of the staple have been penetrated through the work the arm moves toward the work to engage the ends of the projecting 45 legs of the staple with camming grooves on the base to cause the legs to be rocked into parallel relation to the staple-crossbar without substantial deformation intermediate their ends. In accordance with the present improvement the spring for holding the stapling arm raised with 50 respect to the base while a staple is being driven initially may be carried by the arm and be positioned either forwardly or rearwardly of the staple-driver. Preferably, a slideable anvil mounted 55 on the base of the implement is provided with separate sets of camming grooves whereby the staples may be applied to the work with either a permanent stitch or a temporary pin-stitch.

In its preferred form as herein illustrated the 60 invention is embodied in a fastener-applying implement of the type shown and described in United States Letters Patent to Maynard, No. 2,037,334, issued April 14, 1936. Suffice it to state herein that the implement comprises a base 2, a 65 stapling arm 3 pivotally mounted on the base and an actuating lever 4 pivotally mounted on the arm and connected to operate a staple-driver 5. The base 2 is preferably constructed of sheet-metal stamped or embossed to form a generally 70 flat, rectangular top plate 6 bounded by a de-

pending bevel flange 7. Fastened to the top plate 6 of the base 2 adjacent its rearward end is a hinge-block or mounting 8 for the stapling arm 3 which is formed as a hollow magazine for the staples 5. The stapling arm 3 is pivotally mounted on a pin 9 carried by rearwardly-extending ears 10 on the hinge-block 8 with its ends projecting laterally through the depending sides of an inverted U-shaped member 11 attached to the bottom of the arm. The sides of the member 11 10 overlie the sides of the hinge-block 8 on the base 2 to prevent lateral twisting of the arm 3 with respect to the base.

The stapling arm 3 is of channel-shape in cross-section, see Fig. 4, having an inverted channel-shaped core 15 extending longitudinally thereof and secured therein for supporting U-shaped staples 5 straddled thereacross. The forward end of the core 15 is provided with laterally-offset, depending side flanges 16 having laterally-projecting latching lugs 17 thereon. A channel-shaped member 18 is supported between the side walls of the arm 3 with its bottom wall 19 overlying the core 15 in spaced relation thereto to hold the staples in place thereon. The forward end of the arm 3 is closed by a U-shaped gate 20 having a front wall 21 which cooperates with the end of the core to provide a throat 22 through which the staples are driven and side walls 23 which overlie the sides of the core with notches 24 formed therein for cooperation with the lugs 17. The gate 20 is pivotally mounted on the member 18 by means of a pin 25 which extends transversely through oval slots 26 in the side walls of the member with its ends secured to the side walls 23 of the gate. Thus, the pin 25 may pivot on the member 18 to permit the gate 20 to be swung away from the end of the core 15 to open the magazine. Normally, the gate 20 is held in closed position as illustrated in Fig. 1 by the notches 24 in its side walls 23 being yieldingly engaged with the lugs 17 on the depending flanges 16 of the core 15. A hairpin-shaped spring 27 tensioned between the arm 3 and pivot-pin 25 retains the notches 24 in engagement with the lugs 17. The staples 5 in the magazine are advanced along the core 15 toward the throat 22 by means of a pusher 28 and spring 29 connected thereto.

The staple-driver 5 is mounted to reciprocate in the throat 22 at the forward end of the arm 3, being connected to the lever 4 to be operated thereby. The lever 4 is of inverted channel-shape in cross-section having opposite sides 36 overlying the sides of the arm 3 and a front wall 37 overlying the forward end of the arm. The lever 4 is pivotally mounted on the arm 3 by means of a pin 38 extending transversely through the sides of the member 18 and the sides of the lever. Mounted on the inside face of the front wall 37 of the lever 4 is a block 39 having a tongue 40 which extends rearwardly through a suitable orifice in the driver 5. The lever 4 is yieldingly held in raised position with respect to the arm 3, as illustrated in Fig. 2, by means of a relatively weak hairpin spring 41. Surmounting the forward end of the lever 4 is a pad 42 providing a hand-rest to adapt the lever to be manually depressed against the action of the spring 41. Pivotally mounted between the sides of the U-shaped member 18 on the arm 3 is an element 43 which serves the double function of dogging the staples when the gate 20 is open and preventing a complete return of the driver 5 until a full driving stroke has been accomplished; this latter device 75

being more fully described in the Maynard Patent 2,037,334 referred to above. The arm 3 is also provided with a staple-supporter 44 which is mounted for combined pivotal and longitudinal movement to hold the crossbar of each staple *s* being driven against the bottom edge of the driver 5. As thus far described the implement is substantially identical with that illustrated in the Maynard Patent 2,037,334 referred to above.

10 In accordance with the present invention, resilient means are provided for holding the forward end of the stapling arm 3 in raised position above the base 2 until the lever 4 has been depressed with respect to the arm to penetrate the legs of the staple through the work; the resilient means thereafter yielding to permit the arm to move toward the base. As herein illustrated, one suitable means for holding the arm 3 elevated above the base 2 comprises a leaf-spring 50 attached to the arm and engageable with the anvil 60 on the base 2. As illustrated in Figs. 1 to 4, the spring 50 is positioned rearwardly of the driver 5 and has one end 51 attached to the bottom of the stapling arm 3 by means of a screw 52 extending through the spring and bottom wall of the arm and a nut 53 screwed onto the threaded portion of the screw. The nut 53 is tightened against the bottom wall of the arm 3 and is held against turning by its engagement with the opposite sides of the channel-shaped core 45, see Fig. 4. The spring 50 extends downwardly and forwardly and has its free end 54 curved to adapt it to bear against and slide along the top of the anvil 60 on the base 2 rearwardly of the work *w*. The spring 50 of the present invention differs from springs heretofore used for a similar purpose in that it is made of such dimensions or of such material as to have a greater tension than the spring 41 previously described, whereof to hold the arm 3 in raised position with respect to the base 2 until the driver 5 has been operated to drive a staple *s* sufficiently to penetrate its legs through the work.

The anvil 60 is slidably mounted on the base 2 of the implement to selectively align one or the other of two separate sets of camming grooves 61 and 62 with the driver 5. The anvil 60 comprises a flat plate which overlies the top plate 6 at the forward end of the base 2 and is provided with laterally-extending finger-pieces 63 to facilitate sliding it from one to the other of its two positions. The camming grooves 61 and 62 are in the form of slots cut into the top face of the anvil 60 and the two separate sets are spaced longitudinally thereof. The camming grooves 61 are adapted to rock the legs of a staple inwardly toward each other, the outer ends of the grooves being spaced apart a distance substantially equal to the distance between the staple legs. The bottoms of the camming grooves 61 are continuously curved from the top face of the anvil at their outer ends inwardly toward each other and terminate in a common apex 64 at the center, see Fig. 7. The camming grooves 62, on the other hand, are adapted to form a temporary pin-stitch by being arranged in longitudinally-spaced relationship with their inner ends spaced apart a distance substantially equal to the distance between the staple legs. The bottoms of the camming grooves 62 are continuously curved from the top face of the anvil at their inner ends laterally outwardly and terminate at the top face of the anvil at their outer ends.

Instead of curling the legs of a staple as it is being driven the camming grooves 61 or 62 of

the present invention act to rock the legs of the staple about axes having a fixed relation to their points of joinder with the crossbar of the staple without substantially deforming the legs intermediate their ends. Therefore, by the term "rock" as used herein and in the appended claims is meant the swinging movement of the legs about axes which are relatively fixed in relation to the staple without substantial deformation intermediate the ends of the legs in contradistinction to the usual curved clinch caused by a continuous deformation of the legs by the clincher-grooves while the staple is being driven.

The anvil 60 overlies a slot 66 in the top plate 6 of the base 2 having a narrow bridge 67 extending thereacross intermediate its ends, the bridge being of a width corresponding to the space between the two sets of camming grooves 61 and 62 in the anvil 60. The anvil is provided with depending flanges 68 and 69 at its opposite ends adapted to fit closely between the edges of the slot 66 to hold the anvil against turning on the base, and a depending detent 70 on its bottom is adapted to cooperate with the opposite edges of the bridge 67 to retain the anvil in one or the other of its two operative positions. The anvil 60 is yieldingly held against the top plate 6 of the base 2 by means of a spring 75 on a stud 74 depending from the anvil and projecting through the slot 66. The compression spring 75 is mounted on the shank of the stud 74 and acts between a head 76 at the lower end of the stud and a washer 77 on the shank to press the latter against the bottom of the top plate 6 of the base 2 at the opposite sides of the slot 66. One form of the invention having now been described in detail its mode of operation is explained as follows:

The implement is first prepared for operation by sliding the gate 20 upwardly and then rocking it on its pivot-pin 23 to open the forward end of the magazine in the arm 3. A supply of staples *s*, preferably in the form of a stick, is then slid rearwardly onto the core 45 against the action of the pusher 28, the spring 29 yielding for this purpose. When released, the staples are held against movement outwardly of the magazine in the arm 3 by the element 43 until the gate 20 is rocked to its closed position to release the element. The staples *s* are automatically fed forwardly by the pusher 28 under the action of the spring 29 to position the foremost staple in the throat 22. If a temporary pin-stitch is to be formed the anvil 60 is slid rearwardly to position the camming grooves 62 in alignment with the driver 5 and when a permanent stitch is to be made the anvil is slid forwardly to position the camming grooves 61 in alignment with the driver.

The work *w* is positioned in the opening between the anvil 60 and the staple-applying mechanism on the arm 3 and the pad 42 at the forward end of the lever 4 is then depressed. Due to the resistance of the spring 50 acting between the arm 3 and the base 2, the forward end of the arm is held in raised position with respect to the base 2 until the driver 5 has been operated through substantially a complete driving stroke to drive a staple *s* to pierce its legs through the work *w* in the manner illustrated in Figs. 2 and 5. Thereafter, continued pressure on the lever 4 causes the spring 50 to yield and the forward end of the arm 3 to move toward the anvil 60. The engagement of the ends of the legs of the staple *s* with the camming grooves 62 then causes them to be rocked outwardly with respect to the cross-

bar of the staple without substantial deformation intermediate their ends and the crossbar. This rocking movement of the legs of the staple continues during the movement of the arm 3 toward the work until the legs are in substantially parallel relation to the crossbar of the staple to form a pin-stitch in the manner illustrated in Fig. 6. Due to the alinement of the laterally-projecting legs of the staple substantially with its cross bar the stitch may be easily and quickly removed in the manner of withdrawing a pin without mutilating or tearing the work. When the lever 4 is released the springs 41 and 50 act to raise the lever and the driver 5 with respect to the arm 3 and to raise the arm with respect to the base.

When a permanent stitch is to be formed the anvil 60 is slid along the base 2 to aline the camming grooves 61 with the driver 5. To slide the anvil 60 the laterally-extending finger-pieces 63 are grasped between the finger and thumb and the anvil drawn forwardly on the base 2. Due to the inclination of the sides of the depending detent 70 the anvil 60 is cammed upwardly against the action of the spring 75 whereby the detent will ride over the bridge 67 during its forward movement until the depending flange 69 on the anvil engages the end of the slot portion 66. The camming grooves 61 are then alined with the driver 5 and the detent 70 is engaged with the oppcsite side of the bridge 67 to yieldingly hold the anvil 60 in operative position on the base 2. With this last-described adjustment the staple is driven in the same manner as explained above, the arm 3 being held in raised position with respect to the base 2 until the staple is driven to penetrate its legs through the work and thereafter moved toward the work to engage the ends of the legs with the camming grooves 61 as illustrated in Fig. 9. Continued movement of the arm 3 with respect to the base 2 causes the legs of the staple to be rocked inwardly toward each other without substantial deformation intermediate their ends and the crossbar to form a flat permanent clinch.

In Figs. 9 and 10, a modified form of construction of the implement is illustrated. In this form of construction the means for yieldingly holding the stapling arm 3 raised with respect to the base 2 comprises a bowed spring 80 attached to the arm 3 forwardly of the driver 5. As illustrated in the present drawings, the spring 80 has one end attached to the front wall 81 of a gate 82 by means of a screw 83 and is bowed outwardly, downwardly and then inwardly so that its free end 84 overlies the anvil 60 forwardly of the driver 5. Projecting rearwardly from the spring 80 is a lug 82 which seats in a suitable recess in the front wall 81 of the gate 82 to hold the spring from turning about the axis of the screw 83. The gate 82 is similar to the gate 20 illustrated in Figs. 1 to 3 but has the lower rearward edges 85 of its side walls 86 shaped to engage abutments 87 struck outwardly from the flanges 16 on the arm 3. The gate 82 is prevented from being moved upwardly by the pressure of the spring 80 by its pivot-pin 88 being mounted in closely fitting circular bearing apertures 89 in the side walls of the member 18 instead of in oval slots as illustrated in Figs. 1 to 3. The gate 82 is held in closed position on the arm 3 with the lower rearward edges 85 of its side walls 86 in engagement with the abutments 87 by means of the spring 27 which bears on the flat, upper edges 90 of its side walls. Thus, the gate 82 is yieldingly

held in closed position on the arm 3 and prevented from upward movement but is adapted to pivot in the usual manner to open the magazine, the spring 27 yielding for this purpose and engaging the forward edges 91 of the side walls of the gate to hold it open.

The implement illustrated in Figs. 9 and 10 is operated in the same way as explained with respect to the implement illustrated in Figs. 1 to 3. When pressure is applied on the pad 42 the arm 3 is held in raised position with respect to the base 2 by the engagement of the free end 84 of the bowed spring 80 with the work w on the anvil 60 at a point forwardly of the driver 5 until the latter has been actuated to drive a staple to penetrate its legs through the work. The bowed spring 80 thereafter yields to permit the arm 3 to move toward the base to cause the projecting legs of the staples to be rocked into parallel relationship to its crossbar by the camming grooves 61 or 62 in the anvil 60. The spring 80 also has the added function of holding the work in place on the anvil during the driving and setting of the staple.

In Fig. 11 another modified form of construction of the implement is illustrated. In this form of construction a plunger 95 is mounted on the arm 3 forwardly of the driver 5. The gate 96 in this embodiment is similar to that illustrated in Figs. 9 and 10 except that its front wall 97 has brackets 98 and 99 struck outwardly therefrom and apertured to receive the plunger 95. As herein illustrated, the plunger 95 has a portion 100 projecting downwardly through the aperture in the bracket 99, an annular collar 101 adapted to seat against the upper face of the bracket 99 and a reduced shank 102 which projects upwardly through the aperture in the bracket 98. A helical spring 103 is coiled around the shank 102 and acts between the bracket 98 and the annular collar 101 on the plunger 95 to hold the collar seated against the upper face of the bracket 99.

The plunger 95 acts in the same manner as the bowed spring 80 to hold the arm 3 raised with respect to the base 2 until the driver 5 has been actuated to drive a staple to penetrate its legs through the work. The spring 103 then yields to permit the arm 3 to move downwardly with respect to the plunger 95 toward the base 2 to engage the ends of the legs of the staple with the camming grooves 61 or 62 to cause them to be rocked into parallel relation to the crossbar of the staple. The plunger 95 has the same supplementary function as the spring 80 to hold the work in position on the anvil 60.

It will be observed from the foregoing that the present invention provides a construction and arrangement of elements wherein the spring for holding the arm raised with respect to the base is more resistant than the spring for holding the driver in raised position on the arm whereby a staple may be driven to penetrate its legs through the work before the legs are clinched. It will also be observed that the spring may be carried by the arm and positioned either forwardly or rearwardly of the driver.

While the device is herein illustrated as embodied in several preferred forms of construction it is to be understood that modifications may be made in the structure and arrangement of its parts without departing from the spirit or scope of the invention. Therefore, without limiting ourselves in this respect, we claim:

1. In a device of the type indicated, an anvil

adapted to support the work directly thereon, fastener-applying means mounted for movement toward and away from the anvil, a driver carried by the fastener-applying means, a spring for holding the driver in raised position with respect to the fastener-applying means, a second spring carried by the fastener-applying means and having greater resistance than the first-mentioned spring, said second-mentioned spring acting on the anvil to hold the fastener-applying means raised with respect to the work until the driver has been actuated to drive a fastener to penetrate the ends of its legs through the work and thereafter yielding to permit the fastener-applying means to move toward the anvil.

2. In a device of the type indicated, an anvil adapted to support the work directly thereon, an arm mounted for movement toward and away from the anvil, a driver on the arm for applying staples fed thereto, a spring for holding the driver in raised position on the arm, a second spring of greater resistance than the first-mentioned spring acting on the arm forwardly of the driver, said second-mentioned spring operating to hold the arm raised with respect to the work on the anvil until the driver has been actuated to drive a staple to penetrate the ends of its legs through the work and thereafter yielding to permit the arm to move toward the anvil.

3. In a device of the type indicated, a base adapted to support the work directly thereon, an arm mounted on the base for movement toward and away from the latter, a driver on the arm for applying staples fed thereto, a spring for holding the driver in raised position on the arm, and yieldable means of greater resistance than the spring, said means mounted on the arm forwardly of the driver and operating to hold the arm raised with respect to the work on the base until the driver has been actuated to drive a staple to penetrate the ends of its legs through the work and thereafter yielding to permit the arm to move toward the base.

4. In a device of the type indicated, a base adapted to support the work directly thereon, an arm mounted on the base for movement toward

and away from the latter, a driver on the arm for applying staples fed thereto, a spring for holding the driver in raised position on the arm, and a bowed spring of greater resistance than the first-mentioned spring and mounted on the arm forwardly of the driver, said spring acting against the base to hold the arm raised with respect to the work on the base until the driver has been actuated to drive a staple to penetrate the ends of its legs through the work and thereafter yielding to permit the arm to move toward the base.

5. In a device of the type indicated, a base adapted to support the work directly thereon, an arm mounted on the base for movement toward and away from the latter, a driver on the arm for applying staples fed thereto, a spring for holding the driver in raised position on the arm, a plunger mounted on the arm forwardly of the driver, a spring of greater resistance than the first-mentioned spring acting on the plunger, said spring-actuated plunger operating to hold the arm raised with respect to the work on the base until the driver has been actuated to drive a staple to penetrate the ends of its legs through the work and thereafter yielding to permit the arm to move toward the base.

6. In a device of the type indicated, a base adapted to support the work directly thereon, an arm mounted on the base for movement toward and away from the latter, a driver on the arm for applying staples fed thereto, a spring for holding the driver in raised position on the arm, a second spring carried by the arm and having greater resistance than the first-mentioned spring, said second-mentioned spring operating to hold the arm raised with respect to the work on the base until a staple has been driven to penetrate the ends of its legs through the work, and camming means on said base, said camming means being engaged by the ends of the projecting legs of the staple to rock them into parallel relation to the crossbar of the staple without substantial deformation intermediate their ends.

ARTHUR H. MAYNARD. 45
JOSEPH M. GAMBAO.
